RELEASE DEVICE FOR TORQUE WRENCHES

Harry C. Pedersen, Royal Oak, Mich., assignor to
Clyde Engineering and Manufacturing Corporation,
a corporation of Michigan

Application July 14, 1952, Serial No. 298,659

4 Claims. (Cl. 81—52.4)

1

This invention relates to a release device for a torque wrench and more particularly to a release mechanism for a torque wrench of the type disclosed in my co-pending application Serial No. 130,287 since matured into Patent No. 2,634,640, dated April 14, 1953, in which the driving teeth for the drive shaft of the wrench socket are moved out of engagement with one another and held in such position by the engagement of a roller with a skirt carried by the shaft driving head.

Wrenches of the type to which this invention relates are power driven and are frequently mounted in multiple, and are so adjusted that when the resistance of a screw nut or bolt to turning attains a predetermined value, the driving teeth are disengaged from one another so that despite the continuous operation of the prime mover, no further torque will be applied to the screw nut or bolt.

Wrenches of this type have found wide use on production lines, and at times, usually due to faulty lubrication the collar carrying the driving teeth has failed to snap back into driving relation with the wrench shaft driving head, with the result that the wrench would not function and faulty production would result.

The primary object of this invention is to positively assure the meshing of the driving teeth on the sleeve with the driving teeth on the driving head after the teeth have been automatically disengaged by the resistance of the screw nut or bolt to turning.

Another object is to assure relative rotation between the separated driving sleeve and driving head to an extent sufficient to cause the rollers to react against the cam faces of the adjacent portions of the driving head to move the sleeve and head about the axis of the shaft under the influence of the spring which determines the degree of resistance required to throw the wrench into inoperative position.

Among its features the invention embodies forming in each recess in the driving head a shoulder adjacent the side of the recess which is engaged by a roller, a stop lug carried by the sleeve for engagement with the shoulder to positively hold the parts separated, and fingers carried by the sleeve and movable longitudinally thereof for engaging the shoulders and establishing relative rotation between the sleeve and driving head of a magnitude sufficient to cause the skirt of the driving head to move along the surface of an adjacent roller under the influence

of the spring which holds the teeth of the sleeve and driving head in mesh.

In the drawings,

Fig. 1 is a longitudinal sectional view through the drive housing and casing of a torque wrench embodying the features of this invention, showing the wrench in operative position therein,

Fig. 2 is a transverse sectional view taken substantially along the line 2—2 of Fig. 1,

Fig. 3 is a transverse sectional view taken substantially along the line 3—3 of Fig. 1,

Fig. 4 is a side view partially in section of the wrench portion of the device showing the casing removed and the driving teeth of the sleeve and driving head separated,

Fig. 5 is a vertical sectional view through the structure illustrated in Fig. 4 showing the driving teeth in cooperative relation,

Fig. 6 is a fragmentary side view of the sleeve and driving head showing the parts in their separated positions, and

Fig. 7 is a view similar to Fig. 6 illustrating a release finger moving the sleeve and head about their common axis to bring the curved surfaces of the rollers into active contact with the curved cam surfaces on the skirts to cause the parts to snap back into operative position under the influence of the torque-regulating spring.

Referring to the drawings in detail a housing 10 enclosing a prime mover (not shown) has mounted therein an anti-friction bearing 12 in which one end of the drive shaft 14 of the prime mover is mounted to rotate. Carried by the shaft 14 adjacent the anti-friction bearing 12 is a pinion 16 the purpose of which will hereinafter appear. Formed in the housing 10 to one side of the anti-friction bearing 12 and extending parallel to the axis thereof is an opening 18 in which is seated an anti-friction bearing 20. A stem 22 is mounted in the anti-friction bearing 20 and carries at the end thereof on the exterior of the housing a head 24 carrying on its end an annular row of circumferentially spaced teeth 26 having gently inclined cam surfaces 28 therebetween. A gear 30 is fixed to the stem 22 within the housing 10 and this gear meshes with the pinion 16 so that when the prime mover is set into operation the head 24 will be rotated. Opening through the end of the head 24 remote from the stem 22 and extending axially through the head and into the stem is a bore 32 the purpose of which will hereinafter appear.

Secured to the housing in concentric relation to the opening 18 and encircling the head 24 is an elongated tubular casing 34 having adjacent

its end opposite the housing 10 an internally extending annular flange 36 and formed within the casing 34 in longitudinally spaced relation to the flange 36 are longitudinally spaced annular grooves 38 and 40 for the reception of 5 expanding split rings 42 and 43 which form stops the purpose of which will hereinafter appear.

Entering the bore 32 for rotation and longitudinal movement relative to the head 24 and 10 stem 22 is the pilot spindle 50 of a head 52 carrying adjacent the pilot spindle 50 an anti-friction bearing 54. The end of the head 52 remote from the pilot spindle is recessed as at 56 and carries on the end thereof remote from the pilot spindle 15 an annular row of circumferentially spaced teeth 58 having cam surfaces 60 therebetween which are relatively steep and lie at angles reverse to the angles of the cam surfaces 28. A shaft 62 enters the recess 56 and is fixed to the head 52 for rotation therewith and this shaft extends 20 axially from the head in a direction opposite the pilot spindle 50 and in axial alignment therewith. The shaft 62 is provided adjacent the end thereof remote from the head 52 with external screw threads 64 and carries an axial extension 25 66 for engagement with a wrench socket.

Mounted on the anti-friction bearing 54 carried by the head 52 is a collar 70 carrying at the end adjacent the pilot spindle 50 an annular row 30 of circumferentially spaced teeth 72 which are adapted during certain conditions of the operation of the wrench to engage the teeth 26 and effect driving connection between the head 24 and collar 70. Extending between the teeth 72 on the collar 70 are cam surfaces 74 which when 35 the teeth 26 and 72 are engaged are in abutting relation to the cam surfaces 28. Carried by the end of the collar 70 and extending longitudinally from the end thereof remote from the teeth 72 is an annular flange or skirt 73 having extending therethrough and opening through the end thereof remote from the teeth 72 peripherally spaced recesses 76 and the corner of each recess 76 adjacent one side thereof is curved to form a cam surface 79 which merges into the adjacent edge 40 of the flange or skirt, as will be readily understood upon reference to Figures 6 and 7.

A sleeve 80 is mounted on the shaft 62 adjacent the collar 70 and carried by the end of the sleeve 80 adjacent the head 52 is an annular row of 50 peripherally spaced teeth 82 which under normal operation of the wrench mesh with the teeth 58 carried by the head 52. Relatively steep cam faces 84 extend between the teeth 82 and during the normal operation of the wrench frictional 55 engagement of the cam faces 60 of the head 52 with the cam faces of the sleeve 84 is maintained by a relatively stiff spring as will hereinafter be explained. Threaded on the threads 64 of the shaft 62 is a nut 86 and surrounding the shaft 62 and abutting the nut 86 and sleeve 80 is a relatively stiff compression coiled spring 88 which 60 yielding urges the cam faces 84 into frictional contact with the cam faces 60 and the teeth 82 and 58 into mesh. A relatively light coiled spring 90 is seated on the inner end of the bore 32 and engages the inner end of the pilot spindle 50 to 65 yieldingly hold the driving teeth 26 and 72 out of mesh.

The wrench so far described will serve admirably in arresting further turning movement on a screw, nut or bolt when the resistance to turning by the screw, nut or bolt attains a predetermined value, and the value of such resistance can be readily regulated by turning the nut 70

86 to increase or decrease the effort of the spring 88.

In order to prevent wear on the points of the teeth 58 and 82 the sleeve 80 is provided at the end thereof carrying the teeth 82 with an annular longitudinally extending skirt 92 having formed therein and opening through the end thereof remote from the sleeve a group of circumferentially spaced recesses 94 in which are received the portions of the skirt 73 of the collar 70 between the recesses 76 therein. Formed in the corner of each recess 94 adjacent the side thereof nearest the high points of the teeth 82 is an arcuate recess 96. A roller 98 of hardened steel is seated in each recess 96 and when the wrench is in normal operation with the teeth 82 of the sleeve 80 in mesh with the teeth 58 of the head 52, the rollers 98 are accommodated in the recesses 76 below the shoulders 78. See Fig. 1.

When however, the resistance to turning of the shaft 62 attains a predetermined value the cam faces 60 will ride on the cam faces 84 and cause the sleeve 80 to separate from the head or collar 52 against the effort of the spring 88. The relative rotation of the parts will cause the rollers 98 to ride along the curved cam surfaces 79 as suggested in Fig. 7 until the rollers 98 rest thereon adjacent the flat end portions of the skirt 73 as shown in Fig. 6. Thus the engagement of the rollers 98 with curved end portions of the skirt 73 will hold the teeth 58 and 82 out of mesh so as to avoid wear on the points thereof until the wrench is withdrawn from the work and the shaft 62 is free to turn at which time the faces of the rollers will move on the inclined portions of the curved cam faces 79 and under the influence of the spring 88 restore the device to working condition.

The structure so far described serves admirably in freeing the shaft 62 from turning by the prime mover and preventing wear on the points of the teeth 58 and 82 but at times, usually due to faulty lubrication, the sleeve 80 will remain separated from the driving head or collar 52 so that when the device is withdrawn from the work, the rollers 98 will fail to move along the curved cam faces 79 and thus destroy the function of the wrench for the next operation.

In order to overcome this difficulty and effect positive rotation of the sleeve 80 relative to the driving head or collar 52 a shoulder 78 is provided in each recess 76 adjacent each curved cam face 79 on the skirt 73 and each shoulder is provided with a curved outer corner 77 for a purpose to be more fully hereinafter described. Mounted on the sleeve 80 for longitudinal sliding movement between the stop rings 42 and 43 of the casing 34 is a ring or collar 44 having in its inner face an annular groove 46 and an enlarged bore 48. Formed in the skirt 92 of the sleeve 80 between the recesses 94 therein are peripherally spaced grooves 100 and mounted for longitudinal sliding movement in said grooves 100 are fingers 102. Lugs 104 are carried by the fingers 102 and are received in the groove 46 of the ring or collar 44 so that as the ring or collar 44 moves longitudinally on the sleeve 80, the fingers 100 will likewise move relative to the sleeve. The ends of the fingers 102 remote from the lugs 104 project into the recesses 76 in the skirt 73 of the driving head 52 and are rounded as at 108 to form cam faces which under certain circumstances engage the rounded corners 79 to establish positive relative rotation between the sleeve 80 and driving head 75 52 to move the rollers 98 along the curved cam

surfaces 79 a distance sufficient to enable the spring 88 to snap the teeth 58 and 82 into mesh.

In use assuming that the wrench has just been used to complete the driving home of a screw, nut or bolt, and that the teeth 50 are in mesh with the teeth 72; under these conditions the spring 90 will be compressed so that the stop ring 42 is spaced longitudinally from the ring or collar 44 and the teeth 58 and 84 are being held out of mesh by the engagement of the rollers 98 with the curved surfaces 79 on the skirt 73. As the wrench is withdrawn from the work the casing 34 will move longitudinally relative to the inner assembly including the sleeve 80, driving head 52 and shaft 62 so as to bring the stop ring 15 42 into engagement with the ring or collar 44 to thereby positively advance the fingers 192 to positively engage the curved corners 77 so as to establish a positive turning effort between the sleeve 80 and driving head 52 in a direction to move the 20 rollers 98 into a position where they will ride on the curved portions 79 of the skirt 73 under the influence of the spring 88. By thus positively establishing initial rotary motion between the driving head 52 and sleeve 80 the positive restoration 25 of the driving connection between the sleeve 80 and shaft 62 is accomplished and all danger of failure of the wrench is eliminated.

While in the foregoing there has been shown and described the preferred embodiment of this 30 invention it is to be understood that minor changes in the details of construction, combination and arrangement of parts may be resorted to without departing from the spirit and scope of the invention as claimed.

What is claimed is:

1. In a torque wrench of the type having a casing, a prime mover, a driven shaft driven by the prime mover, a yieldingly separable drive clutch member within the casing between the prime mover and the driven shaft which when the wrench is advanced towards the work establishes driving connection between the prime mover and the driven shaft, a pair of separable clutch members within the casing between the driven shaft 45 and the yielding separable drive clutch member, said drive clutch members being adapted to separate and interrupt driving connections between the prime mover and the driven shaft when the resistance to turning of the driven shaft attains 50 a predetermined value, and means within the casing to hold the separable clutch members separated, and means for positively releasing the clutch member holding means comprising longitudinally movable fingers carried by one of said 55 clutch members for advance by the separation of the separable clutch into engagement with the other clutch member to establish a relative rotation between the clutch members.

2. The structure recited in claim 1 in which the means for positively releasing the clutch member holding means comprises cam faces carried by the fingers for engaging the other clutch member and establishing relative rotation between the clutch members, and means carried by the fingers and engageable by the casing upon separation of the separable drive clutch for moving the fingers and engaging the cam faces with the other clutch member.

3. The subject matter recited in claim 2 in which the means carried by the fingers comprises a ring mounted on the clutch member carrying the fingers for longitudinal movement thereon.

4. In a torque wrench of the type having a casing, a prime mover, a driven shaft driven by the prime mover, a yieldingly separable drive clutch within the casing between the prime mover and the driven shaft which when the wrench is advanced toward the work establishes driving connection between the prime mover and the driven shaft, a pair of separable clutch members within the casing between the driven shaft and the yieldingly separable drive clutch, said clutch members being adapted to separate and interrupt driving connection between the prime mover and the driven shaft when the resistance to turning of the driven shaft attains a predetermined value, and means within the casing to hold the separable clutch members separated, means for positively releasing the clutch member holding means comprising, a ring mounted on one of the clutch members for movement longitudinally thereon, a stop ring carried by the casing for engaging the ring and moving it longitudinally on the clutch member toward the other clutch member upon separation of the separable clutch, fingers carried by the ring carrying clutch member and connected to the ring for movement therewith, and cam faces carried by the fingers and engageable with the other clutch member for establishing relative rotation between the clutch members.
